United States Patent Office.

CARL MÜLLER, OF NEW YORK, N. Y., ASSIGNOR TO NICHOLAS MÜLLER, OF SAME PLACE.

Design No. 3,109, dated July 14, 1868.

DESIGN FOR A FIGURE.

The Schedule referred to in these Letters Patent and making part of the same.

TO ALL WHOM IT MAY CONCERN:

Be it known that I, CARL MÜLLER, of the city, county, and State of New York, have invented a new and ornamental Design for a Figure; and I do hereby declare that the following is a full, clear, and exact description thereof, which will enable those skilled in the art to make and use the same, reference being had to the accompanying drawing, forming a part of this specification.

This invention relates to a design for a figure representing a newsboy running along, barefooted, full of excitement, crying out his papers. Under his right arm he carries a bundle of them, and in his left holds out one of them, offering it to some passer-by. His hair is hanging on his forehead, from under his cap; his shirt-bosom is thrown open, and one leg of his patched pantaloons is rolled up, as seen in the drawing.

What I claim as my invention, and desire to secure by Letters Patent, is—

The design for a figure, as herein shown and described.

The above specification signed by me, this 12th day of June, 1868.

CARL MÜLLER.
